UNITED STATES PATENT OFFICE.

GEORGE SOLLITT, OF HASTINGS, NEW ZEALAND.

MEANS FOR PREVENTING RACING IN SCREW-PROPELLED VESSELS.

SPECIFICATION forming part of Letters Patent No. 716,128, dated December 16, 1902.

Application filed January 14, 1902. Serial No. 89,746. (No model.)

To all whom it may concern:

Be it known that I, GEORGE SOLLITT, a subject of the King of Great Britain, residing at Hastings, Hawke's Bay, New Zealand, have 5 invented new and useful Improvements in Means for Preventing Racing in Screw-Propelled Vessels; and I do hereby declare the following to be a full, clear, and exact description of the same.

10 This invention relates to means applicable for use in preventing the engines of screw-propelled vessels largely exceeding their normal speed of working, commonly known as "racing," upon emersion or partial emersion 15 of the propeller, thus avoiding the serious risks attending such action.

According to my improved method the supply of steam to the engines is controlled by means of the compression and rarefaction of 20 air produced by the up-and-down motion of a piston arranged in a cylinder. The lower portion of the cylinder is connected with the external water in such a manner that it shall find access to the under side of the piston, 25 the rise and fall of such piston being governed by the different and varying depths of immersion of the vessel's hull. The apparatus for carrying out this operation consists of a cylinder that is closed at the bottom end 30 and open at the top and which is placed above the propeller-shaft, preferably as far aft in the vessel as the "run" of her stern will permit. This cylinder is in communication with the external water by means of 35 pipes provided with suitable shut-off or regulating valves. Mounted above the cylinder is another cylinder or extension that is provided with a piston and piston-rod, which passes through stuffing-boxes on the top of a 40 dome-shaped upper end of the top cylinder. The piston-rod is connected to counterweights by means of cords passing over pulleys on each side, and these weights counterbalance the weight of her piston. From the cover of 45 the upper cylinder a pipe is led to the engine-room and is in connection with means for operating the throttle-valve governing the admission of steam to the engine. These means consist of a cylinder provided with a 50 piston and piston-rod, the piston-rod being connected to the throttle-valve in any suitable manner, so that by its movement up and

down the valve may be caused to open or close and thus shut off or open the steam-supply.

In the accompanying drawings, Figure 1 is a side elevation of the appliances employed for carrying out the object of this invention. Fig. 2 is an end elevation of the same. Fig. 3 is a sectional end elevation of the same. Fig. 4 is a detail of the means for operating the throttle-valve.

a is the propeller-shaft, above which is mounted upon a suitable stand *b* the short cylinder *c*. This cylinder is closed at the bottom and is open at the top and has openings into it from each side the pipes *d*, that lead downward through the hull *e* of the vessel and are formed with open mouths, so that the outside water may enter therein. These pipes are provided with the shut-off valves *f* for regulating the amount of water to be admitted to the cylinder *c*, and consequently the pressure of water within the cylinder. Secured upon the top end of the cylinder *c* is another cylinder *g*, whose bottom end is open, so as to form a continuation of the cylinder *c*. The upper end of the top cylinder is closed by a dome-shaped cover *h*, provided with stuffing-boxes, through which passes the piston-rod *i*, connected to the piston *j*, fitting within the cylinder *g*. The faces of the piston *j* are preferably concave, while its circumference is formed with a groove, which, with the inner face of the cylinder, forms an annular chamber or space, as shown in Fig. 3, which may be supplied with oil, which will serve the double purpose of lubricating the piston and preventing the passage of air through the cylinder. Suitable cocks *k* may be arranged on the side of the cylinder for feeding oil to the annular space or for drawing off any water or air that might find ingress to the cylinder.

The top end of the piston-rod *i* is provided with a cross-head *l*, to which are attached cords *m*, passing over pulleys *n*, supported by brackets *o* on the top end of the cylinder *g*. These cords have attached to their loose ends the counterweights *p*, that rest in suitable guides in the side of the cylinder and serve to counterbalance the weight of the piston and piston-rod.

Leading from the top end of the cylinder *g*

- is a pipe *r*, that leads to the engine-room, where it is connected to the bottom end of a small cylinder *a*, that is provided with a piston and piston-rod. The top end of the piston-rod of this cylinder is connected by means of the lever *t* with a toothed wheel *u*, that gears with a smaller toothed wheel upon the spindle of a throttle-valve *v*, controlling the passage of steam through the steam-pipe *w*, that leads to the engines.
- The action of the apparatus is as follows: Assuming the vessel to be on an even keel and the screw-propeller wholly immersed, the piston *j* then occupies the upper end of its cylinder, owing to the pressure of water beneath that enters through the pipes *d*. When, however, the stern of the vessel lifts out of the water and the propeller becomes partially emersed, the water will escape from the cylinder, and the pressure beneath the piston is removed, so that it will fall or be drawn down, when, owing to the expansion of the air thus obtained above the piston, and consequently within the pipe *r*, the piston within the cylinder *s* will be drawn down and the spur-wheel *u* turned so as to close the throttle-valve *v*, its turning motion being assisted by means of the weighted arm *x*, attached to it. The supply of steam will thus be shut off or reduced, so that the speed of the engines will be decreased while the propeller is out of the water. Upon the vessel regaining its natural level water will rise once more within the cylinder *g* and force upward the piston *j* and cause the air within the air-pipe *r* to be compressed, so as to force up the piston within the cylinder *s* and open the valve *v* again. The counterweights *p* will assist the piston *j* in its upward movement.
- In practice it will be found advisable to have an independent pressure of air within the air-pipe *r* and the space above the pis-

ton *j* of about two pounds to the square inch, so as to provide for expansion and compression by the downward and upward movement 45 of the piston.

What I claim as my invention, and desire to secure by Letters Patent, is—

1. In appliances for preventing racing in screw-propelled vessels, an air-tight cylinder 50 fitted vertically within the vessel, a chamber beneath the cylinder in communication therewith, pipes leading from the chamber through the hull of the vessel, a piston within the cylinder provided with a piston-rod projecting 55 through the top end of the same and counterweights attached to the piston-rod, in combination with means whereby the up-and-down movement of the piston may be caused to open and close the valve of the steam-pipe leading to 60 the engines, as herein set forth.

2. In appliances for preventing racing in screw-propelled vessels, in combination, an air-tight cylinder fitted vertically within the vessel, a chamber beneath the cylinder communicating therewith, pipes leading from the chamber through the hull of the vessel, a piston within the cylinder provided with a piston-rod projecting through the top end of the cylinder, counterweights attached to the piston-rod, an auxiliary air-tight cylinder provided with a piston and piston-rod connected to gearing adapted to open and close the valve of the steam-pipe leading to the engines, and a pipe connection leading from the top 70 end of the main cylinder to the bottom end of the auxiliary cylinder, as herein specified.

In testimony whereof I have signed this specification in the presence of two subscribing witnesses.

GEORGE SOLLITT.
